UNITED STATES PATENT OFFICE.

MORRIS R. LEVY, OF NEW YORK, N. Y.

SIGN OR BANNER.

SPECIFICATION forming part of Letters Patent No. 323,696, dated August 4, 1885.

Application filed July 3, 1884. (No model.)

To all whom it may concern:

Be it known that I, MORRIS R. LEVY, of the city, county, and State of New York, have invented a certain new and useful Improvement 5 in Signs and Banners, of which the following is such a full, clear, and exact description as will enable others skilled in the art to which my invention appertains to make and construct the same, reference being had to the accompanying drawing, forming part of this specification.

My invention relates to that class of signs and banners having a ground or base of network of twine, thread, cord, silk, or the like. 15 Hitherto the binding, fringe, and parts bearing the inscriptions or designs of such signs and banners have been made of ordinary canvas, muslin, cloth, or the like; but the use of such materials has been attended with certain 20 objections. In the first place, it has been necessary in most instances to paint the background of the parts upon which the inscriptions, designs, &c., have been placed, and this has added to the weight of the sign or banner, 25 beside which the paint has peeled, chipped, or cracked off, giving to the banner or sign an unsightly appearance, thus destroying or injuring the inscriptions and leaving the fabric exposed. Moreover, painting the back- 30 ground of inscriptions or designs has involved considerable expense, and the extra weight has tended to cause the banner to get out of shape, and when such background has not been painted the fabric has rotted by expos- 35 ure to the weather, owing to the character of the material used. So, also, the binding being of like material, gives way under action of the weather unless painted, and there is difficulty in painting it, and there are also the 40 same objections to the paint as upon other parts of the sign or banner. The net-work base or ground has likewise been affected more or less by the influences of the weather.

The object of my invention is to obviate 45 these objections and to produce a sign or banner which shall be light, durable, and economical, and this I do by making the strips, pictures, letters, inscriptions, designs, binding and trimmings when and as desired of or 50 on rubber sheeting or rubber cloth, and using

the same in connection with a net-work, which may also be made water-proof by means of rubber, as hereinafter more fully explained.

In the drawing, A A represent the net-work or ground of a banner, such as is suspended across a street; and B B, the figures, devices, or inscriptions thereon, the strips or pieces forming or bearing the same being of rubber sheeting or cloth, and C is the rope or wire from or on which the same is hung. 60

In making or constructing my improvement I prefer to take the ordinary net-work of twine, cord, or like material, and coat or otherwise treat it with rubber, so as to make it waterproof. This will make this part more 65 durable. I use for the strips, pieces, inscriptions, designs, letters, or other matter to be displayed, rubber sheeting or rubber cloth, stitched, sewed, or otherwise suitably attached to the ground or net work, which may, if desired, be made water-proof, as above stated. The binding and trimming may also be made of the same material, the binding being formed by inclosing a rope or cord within the rubber sheeting around the edges of the sign or banner. 75 The pieces or strips may be either plain or colored, and may be either stamped or cut out in the desired shapes and then attached to the ground-work, or may be inscribed with any designs or characters desired in any suitable manner. The use of colored rubber sheeting for the strips on which the lettering or designs may be placed will obviate the necessity of using paint for producing colored backgrounds, as the coloring-matter may be mixed 80 with the rubber in the course of manufacture. If white-rubber cloth be used the background may be painted in any desired color, leaving the letters or designs white. This construction will render the banner much lighter, and 85 it will therefore not sag or get out of shape, owing to its weight. This material will also be much stronger, as well as lighter, than the material ordinarily used, beside being water- 90 proof.

Having thus described my invention, what I claim as new, and desire to secure by Letters Patent, is—

1. A sign or banner having a base or ground of a net-work, to which is attached, in one or 100

more pieces of any desired size and shape, rubber cloth forming or adapted to receive any desired design or inscription, substantially as described.

5 2. As a sign or banner, one or more pieces of rubber cloth of suitable size and shape, and forming or having thereon letters or designs, in combination with a net-work, substantially as described.

10 3. A sign or banner composed of a net-work

made water-proof by being coated or treated with rubber, in combination with pieces of rubber cloth to form or receive the inscription, letters, or designs, and the binding or fringe, substantially as described.

MORRIS R. LEVY.
